COMPUTER OPERATOR CONSOLE

John A. Macker, Temple City, and Emerson S. Bewley, Covina, Calif., assignors to Burroughs Corporation, Detroit, Mich., a corporation of Michigan

Filed Mar. 28, 1966, Ser. No. 1,655

Term of patent 14 years

(Cl. D26—5)

FIG. 1 is a perspective view taken from the front and left side of a computer operator console showing our new design; the right side being the same as the left side shown; and

FIG. 2 is a front elevational view thereof showing symbols displayed by rear lighting within the console.

The dominant features of our design reside in the portions shown in full lines.

We claim:

The ornamental design for a computer operator console, as shown and described.
